CLAIM

The ornamental design for a computer equipment support shelf, as shown and described.

DESCRIPTION

The design is illustrated by annexed FIGS. 1-7 wherein:

FIG. 1 is a front perspective view of the support shelf, according to the present application;

FIG. 2 is a rear perspective view thereof;

FIG. 3 is a right view thereof;

FIG. 4 is a rear view thereof;

FIG. 5 is a front view thereof;

FIG. 6 is a top view thereof; and,

FIG. 7 is a bottom view thereof.
